RAILROAD CAR JOURNAL LUBRICATOR

Karl A. Klingler, Naperville, Ill.

Application July 7, 1958, Serial No. 746,883

13 Claims. (Cl. 308—90)

My invention relates to improvements in railroad car journal lubricators and has for one object to provide a lubricator which can be placed in the journal box of the usual type of railroad journal associated with the usual brass and wedge and which will maintain without the use of pads, packing or the like, a continuous lubrication of fluid flowing oil on the journal.

Another object of the invention is to provide in connection with such a device means to limit axial movement of the journal in order to protect the oil seal by preventing the journal from slipping out of the seal no matter what kind of lubrication is used.

Lubrication of railroad car axle journal by the use of packing or waste or pads placed in the box and saturated with oil has long been a source of trouble and dissatisfaction. There is a great need for means which makes it possible to lubricate the journal by discharging against the rotating surfaces liquid oil from an oil bath in the bottom of the box. When that is done, however, it becomes essential to provide on the inboard end of the journal an oil seal to prevent splashing out and waste of the freely flowing bath of oil. Therefore, it is exceedingly important that axial movement of the journal which would interfere with the effectiveness or perhaps cause damage of the seal be avoided.

My invention comprises in one unit an apparatus which will lubricate the journal and inhibit axial movement of the journal. In a modification of my device, I use part of the apparatus to inhibit longitudinal movement even though conventional pads, wicks or waste is used.

In each case, my apparatus may be applied to the journal through the usual trap door in the outboard end of the box without any change whatever in the journal, the box or the associated parts, by merely adding to the journal and supporting on the journal my mechanism.

Other objects will appear from time to time throughout the specification and claims.

My invention is illustrated more or less diagrammatically in the accompanying drawings, wherein

Figure 1 is a vertical longitudinal section through a journal box with parts omitted showing the journal in side elevation;

Figure 2 is a section along the line 2—2 of Figure 1.

Figure 3 is a side elevation in part section on an enlarged scale of the outboard end of the bearing and associated parts;

Figure 4 is a section similar to Figure 3 showing a modified form.

Like parts are indicated by like characters throughout the specification and drawings.

The journal box 1 is provided at the front with the usual port adapted to be closed by the pivoted cover 2 through which in the conventional arrangement oil and waste are inserted to lubricate the journal. At the rear end a box is provided with an opening of much greater diameter than the axle 3 and encircling that opening is a pocket 4 adapted to be filled with any suitable packing

2

means, not here illustrated since they form no part of the present invention.

The journal 5 is integral with the axle at the end thereof, is of smaller diameter than the axle and terminates at its outer end in a collar 6, there being a shoulder 7 at the inner end of the journal where the diameter increases from the journal diameter to the axle diameter. The brass 8 rotates on the journal. 9 is the wedge interposed between the brass and the top of the journal box in the usual way. All these parts are standard and usual in railroad practice.

A light sheet metal spring bracket 10 having a central pocket 11 contains a coil spring 12 which seats at one end in the bottom of the pocket 11 and at the other end on a spring pivot 13. The spring pivot 13 rides on the axle insert 14 which is seated in the usual countersink hole in the end of the axle. A pivot extension 15 extends outwardly from the spring pivot 13 projecting through an aperture in the bottom of the cup 11.

Carried by top of the spring bracket 10 is a spacer bracket 16 arcuate in shape as indicated in Figure 2 and inwardly flanged at 17 to support the bronze thrust block 18, which block rides on the journal, being arcuate to fit it and also engages the inner face of the collar 6. Fingers 19 extend inwardly along the axle below but adjacent to the brass.

Carried by the lower portion of the spring bracket 10 is the lubricator drive bracket 20 which extends inwardly to a point behind the collar 6. The brackets 16 and 20 are slotted at 21 in register with apertures 22 in the spring bracket 10. Holding bolts 23 in the holes and slots make it possible to adjust the brackets radially to fit the journal.

Lubricator drive bracket supports a guide block 24, preferably of bronze, arcuate to contact the lower portion of the periphery of the journal, having a plane face to limit by contact with the inner face of the collar 6 outboard movement of the lower portion of the drive bracket 20.

The drive bracket 20 is pocketed at 25 to support the ball bearing 26 on which is rotatably mounted the drive wheel 27 of steel and the lubricating wheel 28 of rubber so that contact of the drive wheel 27 with the inner face of the collar or flange 6 will, as the journal rotates, cause rotation of the lubricating wheel, the lubricating wheel being immersed at its lower periphery at least in the oil bath 29 in the journal box. Proper spacing is accomplished by the use of the removable spacer block 30 to insure that the thrust block 18 and the drive wheel 27 will both be in contact with the inner face of the collar 6, being held thereagainst by the spring 12 to insure that the spring bracket remains in parallelism with the end face of the journal.

The thrust block 18 being interposed between the inner face of the collar 6 and the end of the brass 8 limits inward longitudinal movement of the journal and if as is frequently the case the collar 6 is worn away before the lubricator is installed, all that is necessary to insure contact of the thrust block and the drive wheel with the inner face of the collar is to use a spacer of greater thickness.

The lubricating wheel is pocketed at 31 with weep holes 32 so that even when the car is at rest, if the level of the oil bath is below the wheel fin 33, oil can still run into the pocket 31 through weep hole 32 so as to be available for discharge as soon as the car rotates. The fins 33 and 34 about the periphery of the wheel thus one or both being immersed in the oil will always be available to flow oil diagonally inwardly and upwardly against the under surface of the journal. The axis of rotation of the wheel will be inclined to the journal axis.

In the modified form shown in Figure 4 the lubricating

wheel and the drive wheel are omitted and on the lower side of the journal a spacer bracket 35 quite similar to the drive bracket 20 carries a lower thrust block 36 balancing the thrust block 18. In this case, lubrication may be by any other desired means but the thrust block 18 is still available to inhibit axial movement of the journal.

The use and operation of my invention are as follows:

The spring bracket and the drive and spacer brackets associated together define an adjustable yoke or spider which masks the end of the journal, encloses the journal collar and yieldingly frictionally engage the inner face of the collar. This yoke or spider is by relationship with the brass held against rotation and so is positioned in the journal box by its contact with the journal and the brass alone. This yoke is axially adjustable to compensate for variation in the axial thickness of the journal collar and furnishes a positive spacing means to inhibit by contact with the journal brass excessive axle journal displacement.

At the same time or separately the yoke supports and maintains in working relationship with the journal itself a lubricating device which consists of a single rotating member driven in response to the rotation of the journal and adapted to throw lubricant from an oil bath in the bottom of the box upwardly against the journal surface outside the brass to insure lubrication of the journal. The yoke is adjustable radially to compensate for variation in journal diameters, is adjustable axially to compensate for variation in journal collar axial dimensions and a single size of assembly by the use of a plurality of spacers may be applied to a wide range of journals with respect to initial dimensions or dimensions after wear.

In order to avoid excess oil flow, it will be understood that after oil has leaked through the weep hole 32 and has been thrown out, then as the lubricator rotates at high speed oil will not have time to enter the pocket and the oil thrown out will be that oil adhering to the surface of the rubber lubricating wheel. Thus excess oil discharged at high speed is avoided.

I have illustrated a single lubricating wheel at the lowermost point of the journal but if desired, a plurality of such wheels could be used without departing from the spirit of my invention.

I claim:

1. In a railroad car axle journal box lubricating assembly, a flanged journal, a bracket adapted to hang upon and be entirely supported by the journal, a lubricant distribution wheel and a drive wheel therefor, both mounted for rotation about a common axis on the bracket, a driving connection between the wheels, and means for biasing the drive wheel into frictional driving contact with the inboard face of the flange.

2. In a railroad car axle journal box lubricating assembly, a flanged journal, a bracket adapted to hang upon and be entirely supported by the journal, a lubricant distribution wheel and a drive wheel therefor, both mounted for rotation about a common axis on the bracket, a driving connection between the wheels, and means for biasing the drive wheel into frictional driving contact with the inboard face of the flange, the axis of rotation of the wheel being inclined to the axis of rotation of the journal.

3. In a railroad car axle journal box lubricating assembly, a flanged journal, a bracket adapted to hang upon and be entirely supported by the journal, a lubricant distribution wheel, a drive wheel and a driving connection between them all on the bracket, and means for biasing the drive wheel into frictional driving contact with the flange.

4. In a railroad car axle journal box lubricating assembly, a flanged journal, a bracket adapted to hang

upon and be entirely supported by the journal, a lubricant distribution wheel, a drive wheel and a driving connection between them all on the bracket, means for biasing the drive wheel into frictional driving contact with the flange, there being an oil pocket in the distribution wheel open at the top toward the journal and a bleeder hole communicating with the pocket through the face of the wheel furthest removed from the journal.

5. In a railroad car axle journal box lubricating assembly, a flanged journal, a bracket adapted to hang upon and be entirely supported by the journal, a lubricant distribution wheel, a drive wheel and a driving connection between them all on the bracket, means for biasing the drive wheel into frictional driving contact with the flange, there being an oil pocket in the distribution wheel open at the top toward the journal and a bleeder hole communicating with the pocket through the face of the wheel furthest removed from the journal, and a plurality of circular flanges extending outwardly from the periphery of the lubricant distribution wheel.

6. In a railroad car axle journal box lubricating assembly, a flanged journal, a bracket adapted to hang upon and be entirely supported by the journal, a lubricant distribution wheel, a drive wheel and a driving connection between them all on the bracket means for biasing the drive wheel into frictional driving contact with the flange, said means including a yoke adapted to mask the outer end of a railroad journal, and radially opposed and radially adjustable brackets on the yoke overhanging the journal flange, the drive and distribution wheels being rotated on the lower of the two brackets.

7. In a railroad car axle journal box lubricating assembly, a flanged journal, a bracket adapted to hang upon and be entirely supported by the journal, a lubricant distribution wheel, a drive wheel and a driving connection between them all on the bracket, means for biasing the drive wheel into frictional driving contact with the flange, said means including a yoke adapted to mask the outer end of a railroad journal, radially opposed and radially adjustable brackets on the yoke overhanging the journal flange, the drive and distribution wheels being rotated on the lower of the two brackets, and a thrust block carried by the upper bracket adapted to engage the inner plane surface of the journal flange.

8. In a railroad car axle journal box lubricating assembly, a flanged journal, a bracket adapted to hang upon and be entirely supported by the journal, a lubricant distribution wheel, a drive wheel and a driving connection between them all on the bracket, means for biasing the drive wheel into frictional driving contact with the flange, said means including a yoke adapted to mask the outer end of a railroad journal, radially opposed and radially adjustable brackets on the yoke overhanging the journal flange, the drive and distribution wheels being rotated on the lower of the two brackets, and a spring interposed between the end of the journal and the yoke biasing it axially away from the journal end to hold the thrust block and drive wheel in working contact with the flange.

9. In a railroad car axle journal box lubricating assembly, a flanged journal, a bracket adapted to hang upon and be entirely supported by the journal, a lubricant distribution wheel, a drive wheel and a driving connection between them all on the bracket, means for biasing the drive wheel into frictional driving contact with the flange, said means including a yoke adapted to mask the outer end of a railroad journal, radially opposed and radially adjustable brackets on the yoke overhanging the journal flange, the drive and distribution wheels being rotated on the lower of the two brackets, a thrust block carried by the upper bracket adapted to engage the inner plane surface of the journal flange, and a spring interposed between the end of the journal and the yoke biasing it axially away from the journal end to hold the thrust block and drive wheel in working contact with the flange.

10. In a railroad car axle journal box lubricating assembly, a flanged journal, a bracket adapted to hang upon and be entirely supported by the journal, a lubricant distribution wheel, a drive wheel and a driving connection between them all on the bracket, means for biasing the drive wheel into frictional driving contact with the flange, said means including a yoke adapted to mask the outer flanged end of a railroad axle, radially opposed, radially adjustable brackets carried by the yoke, overhang the axle flange, a bearing on the lower bracket for the drive wheel, a thrust block carried by the upper bracket to engage the journal and having a plane surface adapted to engage the journal flange, and a guide block associated with the lower bracket to engage the underside of the journal.

11. Means for limiting axial displacement of a flanged railroad car journal comprising a yoke adapted to extend across the end of the journal and having diametrically opposed brackets adapted to extend inwardly across the flange and along the journal, thrust blocks carried by the brackets, means for radially adjusting the brackets to bring the thrust blocks into diametrically opposed contact with the journal and yielding means for biasing the yoke axially away from the journal to hold the thrust blocks in engagement with the inner wall of the flange.

12. Means for limiting axial displacement of a flanged railroad car journal comprising a yoke adapted to extend across the end of the journal and having diametrically opposed brackets adapted to extend inwardly across the

flange and along the journal, thrust blocks carried by the brackets, means for radially adjusting the brackets to bring the thrust blocks into diametrically opposed contact with the journal and yielding means for biasing the yoke axially away from the journal to hold the thrust blocks in engagement with the inner wall of the flange, and means for maintaining the yoke in position with one of the thrust blocks immediately above the axis of the journal.

13. Means for limiting axial displacement of a flanged railroad car journal comprising a yoke adapted to extend across the end of the journal and having diametrically opposed brackets adapted to extend inwardly across the flange and along the journal, thrust blocks carried by the brackets, means for radially adjusting the brackets to bring the thrust blocks into diametrically opposed contact with the journal and yielding means for biasing the yoke axially away from the journal to hold the thrust blocks in engagement with the inner wall of the flange, and means for maintaining the yoke in position with one of the thrust blocks immediately above the axis of the journal, said means including spaced fingers extending inwardly from the yoke on opposite sides of the journal above the horizontal plane thereof.
